UNITED STATES PATENT OFFICE

2,542,452

SELECTIVE LETTER ORNAMENTATION
FOR JEWELRY

Carl A. Anderson, Cranston, and Olof V. Anderson, Covesett, R. I., assignors to Anderson Tool & Die Works, Inc., a corporation of Rhode Island

Application March 13, 1947, Serial No. 734,386

2 Claims. (Cl. 40—140)

1

The present invention relates to the jewelry art, and has particular reference to a novel ornamentation therefor.

The principal object of the invention is to provide a jewelry construction for selectively receiving ornamentation such as initial letters and the like.

Another object of the invention is to provide a jewelry base into which selected ornamentations may be releasably received.

Still another object is to provide a jewelry base adapted to snap receive stamped out initials, the parts being designed to simulate solid constructions.

A further object of the invention is to provide a selective ornamentation having a multi-color effect.

With the above and other objects and advantageous features in view, the invention consists of a novel arrangement of parts more fully disclosed in the detailed description following, in conjunction with the accompanying drawings, and more specifically defined in the claims appended thereto.

In the drawings:

Fig. 1 is a perspective view of a tie holder embodying the novel invention;

Fig. 2 is an enlarged perspective view of the ornamental portion of Fig. 1, parts being broken away;

Fig. 3 is a section on the line 3—3 of Fig. 2;

Fig. 4 is a side view of one ornament;

Fig. 5 is a front view of the ornament of Fig. 4;

Fig. 6 is a section showing a modified shape for the ornament;

Fig. 7 is a section showing another modified shape for the ornament; and

Fig. 8 is a perspective view showing the ornamentation applied to a different form of tie holder.

It has been found desirable to provide jewelry such as tie holders, cuff links, lockets, pins and the like with bases designed to receive snap-in ornamentation such as initials, the parts being conformed to simulate a solid construction, and being arranged to provide a multi-color effect whenever desired. To this end, we form an ornament base with spaced raised holding elements which are adapted to snap receive the ends of a metal ornament such as an initial, and we conform the base and the ornament to simulate a solid construction. We further provide a seat for a color background which cooperates with cut out portions of the ornaments to provide a two-tone or a vari-toned ornamental effect.

2

Referring to the drawings, which illustrate tie holders to which the invention is applied, the tie holder 10 has an ornamental front portion 11 and a back grip element 12 which cooperates with the front portion to grip a tie and a shirt hem therebetween. An ornament housing 13 is mounted on the front portion, preferably by soldering, and includes a base plate 14, ends 15, 16, and sides 17, 18, the ends and sides being shaped to conform to ornaments, as hereinafter described. Transverse parallel lock bars 19 are mounted between the sides 17, 18, vertically spaced above the base plate 14 as indicated in Fig. 3, and horizontally spaced to define an ornament compartment 20. The illustrated embodiment discloses three compartments 20, to receive three ornaments.

Novel ornaments 21, see Figs. 4, 5, are provided, preferably in the form of cut-out initials, the ornaments being stamped from resilient sheet metal and shaped as illustrated in Fig. 2, with raised upstanding arcuate faces 22, a forward generally sloping edge 23, and a rear rounded edge 24 having a sharply turned end 25 to provide a projecting portion 26. The ornament is preferably slightly recessed at its sides 27, 28 to provide side spacer tabs 29 adjacent the rear edge and side spacer tabs 30 adjacent the front edge, as illustrated in Figs. 4 and 5.

When mounting an ornament 21 in a compartment 20, the front edge 23 is inserted under one lock bar 19, and the rear edge 24 is snapped past the next lock bar 19, whereupon the ornament becomes locked in place as illustrated in Fig. 2, with the spacer tabs 29 and 30 locating the ornament between the sides 17 and 18; the sides 17 and 18, as previously stated, conform to the outline and shape of the ornament. A color sheet 31 is preferably positioned over the base plate 14, and the cut out portions of the ornament disclose the color sheet 31 to give a multi-color effect, as shown in Fig. 1.

We have disclosed a curved ornament in Figs. 1 to 5, but any suitable shape may be utilized. The ornament 32, see Fig. 6, is generally triangular, with plane surfaces 33 and 34, but has the same type of front edge 35 and the same type of rear edge 36 to cooperate with the lock bars 19 and the compartments 20 as heretofore described.

Another suitable ornament shape is disclosed in Fig. 7, wherein the ornament 37 has a dished upper portion 38, a sloping front portion 39 and an arcuate rear portion 40, the front edge 41 and the rear edge 42 being similar to the construc-

tions heretofore described, for cooperation with the lock bars 19 and the compartments 20.

Any desired number of compartments 20 may be provided, and the shape and arrangement of the compartments may be suitably modified, to provide different ornamental effects. Thus, referring to Fig. 8, the tie holder 43 has a tapered front element 44 and the compartment 45 is at the forward edge and is of quarter round type, to receive a quarter round initial 46 which has its forward edge 47 positioned under a forward lock bar 48 and its rear edge 49 shaped as hereinbefore described to snap beneath a rear lock bar 50. A backing color strip 51 may be provided, if desired.

Although we have described the invention as applied to a tie holder, other jewelry items such as cuff links, buckles, lockets, pins and the like may be formed to embody the invention, and the size, shape, and arrangement of the ornaments may be varied as desired, within the spirit and the scope of the invention as defined in the appended claims.

We claim:

1. An ornamentation for jewelry, comprising a compartment having a base plate and upstanding sides, spaced intermediate rigid lock bars mounted between said sides and positioned above the base plate, and an ornament of resilient material having an upstanding face portion, a sloping front edge positioned under one lock bar to rest on the base plate, and an arcuate rear edge snapped past a second lock bar, whereby the front and rear edges of the orna-

ment cooperate with spaced lock bars to removably retain the ornament in the compartment.

2. An ornamentation for jewelry, comprising a compartment having a base plate and upstanding sides, spaced intermediate rigid lock bars mounted between said sides and positioned above the base plate, and an ornament of resilient material having an upstanding face portion, a sloping front edge positioned under one lock bar to rest on the base plate, and an arcuate rear edge snapped past a second lock bar, whereby the front and rear edges of the ornament cooperate with spaced lock bars to removably retain the ornament in the compartment, the sides of the ornament having tabs at the front and rear edges forming spacer elements for centering the ornament between the compartment sides.
